UNITED STATES PATENT OFFICE.

HENRY WATERS, OF BISBEE, ARIZONA.

SHOE STRETCHER.

Application filed June 16, 1921, Serial No. 478,101. Renewed August 8, 1922. Serial No. 580,546.

To all whom it may concern:

Be it known that I, HENRY WATERS, a citizen of the United States, and a resident of Bisbee, in the county of Cochise and State 5 of Arizona, have invented certain new and useful Improvements in Shoe Stretchers, of which the following is a specification.

This invention relates to stretching devices especially adapted for use in shoes.

10 An important object of this invention is to provide a shoe stretcher having novel means whereby either the forward or rear end of the stretcher body may be readily spread for stretching either the toe or intermediate portion of a shoe.

A further object of the invention is to provide a shoe stretcher comprising means whereby the shoe may be stretched longitudinally.

20 Other objects and advantages of the invention will be apparent during the course of the following description.

In the accompanying drawing:

Figure 1 is a perspective of the improved 25 shoe stretcher.

Figure 2 is a central vertical longitudinal sectional view through the same.

Figure 3 is a group perspective of a spreading device embodied in the invention.

30 Figure 4 is a group perspective of a hinge embodied in the invention.

Figure 5 is a perspective of a hinge pin adapted for use in connection with the hinge illustrated in Figure 4.

35 Figure 6 is a detailed horizontal sectional view through the improved stretcher, the view illustrating the application of the spreading means for the movable sections.

Figure 7 is a perspective of a cross head 40 forming a part of the invention.

In the drawing the numerals 5 designate a pair of similarly formed coacting sections having their opposed sides formed with longitudinally curved grooves 6 defining a 45 channel within which a spreading member generally designated by the numeral 8 is slidably arranged. With reference to Figure 6 it will be observed that the intermediate portions of the grooves 6 have their bottom walls formed with depressions or

50 notches 10 which receive the stretching block 8 whereby the sections 5 may flatly contact with each other. When the spreading block 8 is positioned within the depressions or 55 notches 10 it is in what might be termed a

neutral position since neither the forward nor the rear end of the device is spread.

However, the grooves 6 gradually decrease in depth towards the ends of the sections 5 from the depressions 10 so that as the 60 spreading block 8 is moved either forwardly or rearwardly the sections 5 will be spread.

The spreading member 8 comprises sections 12 and 13, the section 13 being provided with ears 14 extended on opposite sides 65 of the section 12 and pivotally connected to the same by means of a pin 15. By reason of this construction the spreading block generally designated by the numeral 8 is permitted to partake of free sliding movement in the channel formed by the opposed grooves 6 which are curved longitudinally. The forward end of the section 12 is rounded as indicated at 16 and is received within a 70 transversely curved groove in the rear portion of the section 13.

The means for moving the adjusting block 8 longitudinally of the sections 5 includes 75 a feed screw 18 having its forward end formed with a reduced neck 20 terminating in an enlarged head 21 preferably of spherical formation. The head 21 is adapted to enter an opening in the section 12 by means of a transverse slot 24 extending out through one side of the section 12 and having screw 80 threads whereby a retaining screw 25 may be threaded into the section for holding the head 21 in position.

85 A cross head 28 is arranged in registering recesses 30 in the opposite sides of the sections 5 and is provided with a transverse interiorly screw threaded opening 31 for the reception of the feed or adjusting screw 18. Pins 32 extend from the ends of the cross head and are freely received in openings 34 extended out through the sides of the sections 5. When the feed screw 18 is rotated the same will be moved longitudinally for imparting a corresponding movement to the spreading block 8 for separating either the forward or rear portions of the device.

100 The rear portion of the feed screw is provided with a handle 35 by means of which the feed screw may be manually rotated 105 for adjusting the width of the device. When it is desired to stretch the shoe longitudinally a heel section 36 having a longitudinally slotted arm 37 may be connected to the feed screw by means of a nut 38 110

threaded on the screw and having obliquely extending slots 40 which receive the sections of the arm defined by the slot 41 in the same.

- 5 The sections 5 are connected for sliding and hinged movement with relation to each other by means of pairs of hinged plates 40 secured to the rear ends of the sections 5 and having aligned eyes or barrels 41 50 which slidably receive a squared hinge pin 42. As illustrated in Fig. 6 the squared hinge pin 42 extends beyond the ends of the outer hinge barrels 41 and is formed with heads 46 which constitute stop elements to limit the sliding movement of the sections with relation to each other. The sections 5 may also partake of a hinged movement with relation to each other since the squared hinge pin 42 is formed of a 55 pair of sections pivotally connected as indicated at 48. The pivotal connection 48 of the hinge pin 42 is between the barrels 41 and permits the forward portions of the spreader sections 5 to be swung outwardly 60 when the member 8 is advanced.

25 The toe of the shoe may be slightly elevated by means of a toe plate 50 having a shank 51 which is slidable between the sections 5 and which is provided with a base 65 plate 52 slidable in the grooves 6.

30 As illustrated in Figure 3, the rear portion of the base plate 52 is formed with rearwardly directed apertured ears 54 adapted to be arranged on opposite sides 70 of and pivotally connected to the forward portion of the section 12 of the spreading member 8 so that the longitudinal movement of the screw 18 will result in the sliding movement of the toe plate 50 which may 75 be curved transversely or otherwise formed. In the use of the improved stretcher the toe plate 50 is applied to the section 12 only when it is desired to force the toe of the shoe upwardly.

40 45 Having thus described the invention what I claim as new and desire to secure by Letters Patent is:—

1. A shoe stretcher comprising a pair of

sections, hinge plates secured to the rear ends of said sections and having aligned barrels, a hinge pin passed through said barrels and inclusive of pivotally connected sections whereby the sections may partake of a hinge movement with relation to each other, and a spreading member arranged between said sections. 55

2. A shoe stretcher comprising a pair of sections, hinged plates secured to the rear ends of said sections and having aligned barrels, a hinged pin passed through said barrels and inclusive of pivotally connected sections whereby the sections may partake of a hinged movement with relation to each other, a spreading member arranged between said sections, and a feeding device associated 60 with said spreading member.

3. A shoe stretcher comprising sections, hinge plates secured to the rear ends of the sections and having aligned barrels, and a hinge pin passed through said barrels and 65 inclusive of pivotally connected sections whereby the sections may partake of a hinge movement.

4. A shoe stretcher comprising sections, hinge plates secured to the sections and 70 having aligned hinge barrels, and a square hinge pin passed through said barrels and being of a greater length than the space between the ends of said barrels whereby the sections may partake of sliding movement 75 with relation to each other, said hinge pin being composed of a pair of pivotally connected sections.

5. A shoe stretcher comprising sections, hinge plates secured to the sections and having aligned hinge barrels, a square hinge pin passed through said barrels and being of a greater length than the space between the ends of said barrels whereby the sections may partake of sliding movement with relation to each other, said hinge pin being composed of a pair of pivotally connected sections, and means to separate said first 80 named sections. 85 90

HENRY WATERS.
